US0D1011567S

(12) **United States Design Patent** (10) **Patent No.:** **US D1,011,567 S**
(45) **Date of Patent:** **** Jan. 16, 2024**

(54) **LED LIGHT**

(71) Applicant: **Dongguan Kafulle Electronics Co., Ltd**, Dongguan (CN)

(72) Inventor: **Ping Zhang**, Shenzhen (CN)

(73) Assignee: **Dongguan Kafulle Electronics Co., Ltd**, Dongguan (CN)

(**) Term: **15 Years**

(21) Appl. No.: **29/790,565**

(22) Filed: **Dec. 3, 2021**

(51) **LOC (14) Cl. 26-03**

(52) **U.S. Cl.**

USPC **D26/24; D26/63**

(58) **Field of Classification Search**

USPC D26/24, 37, 44, 61, 63, 64, 72, 74, 93,
D26/104, 106

CPC F21S 6/00; F21S 8/00; F21S 8/04; F21S
8/033; F21S 8/02; F21S 9/02; F21L

(57) **CLAIM**

The ornamental design for a LED light, as shown and described.

DESCRIPTION

FIG. 1 is a perspective view of a LED light, showing my new design;

FIG. 2 is another perspective view thereof;

FIG. 3 is a perspective view showing the design in an open configuration;

FIG. 4 is another perspective view showing the design in an open configuration;

FIG. 5 is a front view thereof;

FIG. 6 is a rear view thereof;

FIG. 7 is a left side view thereof;

FIG. 8 is a right side view thereof;

FIG. 9 is a top plan view thereof; and,

FIG. 10 is a bottom plan view thereof.

The broken line showing of the LED light is for the purpose of illustrating portions of the article and forms no part of the claimed design.

1 Claim, 10 Drawing Sheets
